UNITED STATES PATENT OFFICE.

EUGENE CHILDS AND WILLIAM SANGSTER, OF BOSTON, MASSACHUSETTS,
ASSIGNORS TO FRANKLIN W. PITCHER, OF SAME PLACE.

TOE-CALK MACHINE.

SPECIFICATION forming part of Letters Patent No. 590,451, dated September 21, 1897.

Application filed January 31, 1896. Serial No. 577,499. (No model.)

To all whom it may concern:

Be it known that we, EUGENE CHILDS and WILLIAM SANGSTER, of Boston, in the county of Suffolk and State of Massachusetts, have 5 invented certain new and useful Improvements in Toe-Calk Machines, of which the following, taken in connection with the accompanying drawings, is a specification.

The object of this invention is to provide 10 an improved mechanism for forming from a continuous metal bar spurred toe-calks complete and in readiness for attachment to the red-hot horseshoe.

It is well known to those skilled in the art 15 to which this invention relates that the short piece of steel which constitutes the toe-calk is provided with a lateral spur at one end which is driven into the heated shoe and serves to hold the calk in its proper place 20 until the calk and shoe are welded together.

Our invention is in the nature of an improvement upon that set forth in the United States Patent No. 508,544, granted November 14, 1893, to T. B. Huestis, for a machine for 25 making toe-calks for horseshoes.

One feature of our invention relates to the anvil-block, which has a defined ledge for the calk-blank and is recessed to receive the stationary cutting-die, and the reversible anvil 30 having on each side a plurality of cutting or spur-forming edges.

Another feature is a pivoted rest or support for the red-hot end of the metal bar from 35 which the calks are being formed, such pivot permitting the support to be swung out of the way of its pincers when the bar has become much shortened.

Other novel features include an adjustable stop or gage adapted to regulate the precise 40 length of metal to be cut off for a calk and capable of being turned back when access to the dies is desired, and also a push-off device working through the anvil-block against the side of the completed calk to positively dis- 45 lodge it in readiness for the next one.

In the drawings, Figure 1 is a front view of the machine, Fig. 2 a left end elevation thereof, and Fig. 3 a top plan. Figs. 4 and 5 are transverse and longitudinal sections on 50 the lines 4 4 and 5 5 of Fig. 3. Fig. 6 is a perspective view of the anvil-block, showing the stationary cutter and reversible anvil.

Figs. 7, 8, and 9 are elevations of the cams which actuate the dies which press out the metal for the spur and shape it by successive 55 blows.

A represents the frame of the machine, A' the driving-shaft, and *a* the gearing by which power is communicated to the cam-shaft B, mounted in rigid hangers B' and having a series of cams *b*² *b*³ *b*⁴ *b*⁵ *b*⁶ *b*⁷. These cams actuate the pivoted levers respectively bearing on them, and thereby operate the tools or dies to sever a calk length of metal from the tip of the heated bar and to form a spur there- 60 on, as herein explained.

The red-hot end of the bar enters the machine from the left in Figs. 1 and 3 and from the right in Fig. 5, as indicated in dotted lines. Its forward portion rests upon the 70 ledge *c* of the anvil-block C, Fig. 6, and it is held firmly thereon during the severing and spur-forming operations, as best shown in Fig. 4. The cam *b*² acts on lever D, centrally pivoted, and causes the clamp D', which is 75 held adjustably in the recessed head of said lever, to press steadily upon the heated bar, here shown of triangular form. The adjusting-screws *d*, threaded through the walls of such recessed head, permit the accurate setting of the clamp and the firm holding of the calk-blank during the severing and spur-forming operations. A spring *d'* keeps the friction-roll of the lever D closely pressed 80 upon its cam and tends to release the bar. 85

The reverse position of the clamping mechanism is shown in Fig. 2, the cam having turned so as to withdraw the clamp D' a slight distance, enabling the calk to be removed and the heated bar to be again fed forward 90 by the operator.

The anvil-block C is mounted upon an upright E of the frame and is fixed firmly thereon by set-screws or the like. The anvil C' is a rectangular die located in a corresponding 95 recess at the end of the ledge *c*, Fig. 6, and held firmly in position. It is of hardened steel and is reversible, so as to bring its eight lateral edges into wear successively—that is, to permit reversal, when desired. The wear 100 comes principally along the angle where the outer face and upper edge meet, and it is a great advantage to renew the anvil by giving it a quarter-turn when required.

At the opposite end of the ledge *c* the stationary cutting-die *F* is rigidly held and may be reversible, if desired; but as the forging-blows to which the anvil is subjected do not come upon said die the wear upon it is not so serious. The movable cutter *F'* is mounted upon the pivoted lever *f*, actuated by the cam *b*³ to sever from the clamped bar a calk length of the heated metal.

- 10 Figs. 2, 3, and 5 represent a feature of this invention consisting of a movable support *G* for the heated end of the bar. Such support retains its position until the bar, which is gradually advanced through it, becomes quite 15 short and too hot to be held in the hands. Said support then needs to be removed out of the way of the pincers. We therefore pivot it or otherwise movably attach it on the outer face of the upright *E*, which is provided with 20 two projecting rests *g*, one to support it when in use and the other to hold it when swung out of the way. If the support were rigid or immovable, a foot or two of each bar would be wasted, as the pincers could not approach 25 the anvil. The adjustable pivoted stop, which regulates the length of the calk by stopping the advance movement of the bar, is best shown in Fig. 5. It consists of a stout standard *H*, having a horizontal arm *H'*, with a 30 rigid depending finger *h*, the tip of which extends to the side of the anvil *C'* and stops the advancing bar at the proper point. The arm *H'* is threaded and furnished with a check-nut each side of the standard through which 35 it passes, so that an exact adjustment is secured. The foot of the standard extends inwardly toward the anvil and is pivoted at the heel at *i* between two ears *I*, so that the device may be turned back out of the way when 40 access to the anvil is desired. A set-screw *I'* holds the parts in operative position at other times.

The spur is formed on the forward end of the bar or calk section by two dies *j*, which 45 act simultaneously on opposite sides of the extreme tip of the bar, and by another die *k*, which hammers the spur (during its formation) against the side of the anvil, acting thus in a plane at right angles to the first two. 50 These two punch outwardly and draw downwardly without detaching so much of the red-hot metal as is necessary to form the spur by repeated blows, given by the action of cams *b*⁴ and *b*⁵ upon their levers *J* and *J'*, alternating with the blows given by die *k* as its lever *K* is actuated by the face-cam *b*⁶. The increasing size of the swells on cam *b*⁴, Fig. 7, causes its die to advance somewhat farther with each successive blow, thus gradually 60 elongating the spur.

After the calk is finished by the completion of its spur the push-off devices act to dislodge it from the ledge *c* of the anvil, and it drops down through the open center of the 65 bed of the machine and is carried by gravity down a slide or incline (not shown) and allowed to cool. The push-off apparatus (shown

in Figs. 1, 2, 3, and 4) forms a part of this invention. Two reciprocating rods *L* are shown, one of which works through the anvil-block *C* and the other close beside its spur-forming end. A light standard *l* supports the intermediate portion of these rods, and a surrounding coiled spring *L'* is interposed between a nut adjacent to such standard and the upright *E* of the frame. These rods are pressed suddenly forward at the proper moment to dislodge the calk by the action of cam *b*⁷ on the vibrating arm *M M'*, pivoted on shaft *m*. The springs *L'* push 80 back the rods *L* and restore the parts to the position shown in Figs. 2 and 4. A stop *N* limits this rearward movement. Adjusting-screws are shown at the junction of rods *L* and lever *M'*. 85

We claim as our joint invention—

1. In a toe-calk machine, the recessed anvil-block, having a calk-forming ledge, and the cutter and reversible anvil for cutting and forging, secured to said block, in combination with a clamp for holding fast the heated end of the bar, movable dies for forming a spur upon its forward end, and a cutting-die for severing the calk, substantially as set forth. 90

2. In a toe-calk machine, the anvil-block, the clamp serving to hold the heated bar thereon, the spur-forging dies and the cutters, in combination with a movable support for the hot end of the bar before and after 100 the calk is severed, such support being withdrawn out of the way of the pincers when required, substantially as set forth. 95

3. In a toe-calk machine, the anvil-block, the clamp and bar-support, and the forging-dies and cutters, in combination with an adjustable pivoted stop consisting of a normally vertical standard pivoted to the frame, an adjustable horizontal arm extending from 105 said standard toward the dies, and a vertical 110 finger depending from said arm to engage the end of the stock, substantially as set forth.

4. In a toe-calk machine, the anvil, stop, clamp, forging-dies and cutters, in combination with a push-off mechanism, comprising 115 the reciprocating rods *L* working through and near the anvil-block, the retracting-spring *L'* surrounding said rods, the standard *l* serving to support said rods and control said spring, and with the vibrating lever *M m M'* and its 120 cam *b*⁷ serving to give a quick stroke to the push-off rods, the stop *N* limiting the rearward movement of the lever, substantially as 125 set forth.

In testimony whereof we have signed our 125 names to this specification, in the presence of two subscribing witnesses, on this 20th day of November, A. D. 1895.

EUGENE CHILDS.
WILLIAM SANGSTER.
